UNITED STATES PATENT OFFICE.

WILL C. NEAHR, OF DENVER, COLORADO, ASSIGNOR, BY MESNE ASSIGNMENTS, TO THE DENVER ROCK DRILL MANUFACTURING COMPANY, OF DENVER, COLORADO, A CORPORATION OF DELAWARE.

CROSSING SIGNAL.

Application filed November 28, 1916. Serial No. 133,977.

To all whom it may concern:

Be it known that I, WILL C. NEAHR, a citizen of the United States, residing at Denver, in the county of Denver and State of Colorado, have invented certain new and useful Improvements in Crossing Signals, of which the following is a specification.

The present invention relates to signals, and more particularly those of a warning character for railroad crossings and the like, wherein a movable visual member is actuated upon the approach of a train.

One of the primary objects of the invention is to provide a movable signal of this character that is effective in its warning, and includes in its operative mechanism, means for stopping the signal in a predetermined position, and which position is recognized by railroad and other authorities as "safety" or "clear".

Another and important object is to provide means that is simple in its character, and yet quickly effective to stop the signal at the desired point and prevent its coasting or undue movement after it reaches the desired position.

The preferred embodiment of the invention is illustrated in the accompanying drawings, wherein:

Figure 1 is a side elevation of the signal apparatus, the casing being shown in section.

Figure 2 is a view at right angles to Figure 1.

Figure 3 is a detail view partially in section of a portion of the gearing.

Figure 4 is a sectional view at right angles to Figure 3.

Figure 5 is a detail sectional view through the rock shaft and illustrating the motor operated circuit controller.

Figure 6 is a detail view partially diagrammatic in its character of the electric circuits.

Figure 7 is a detail sectional view through the signal member.

Figure 8 is a detail view of the motor brake.

Similar reference numerals designate corresponding parts in all the figures of the drawings.

In the embodiment illustrated, a suitable casing is employed, comprising a base 9 on

which is mounted a boxing 10 hinged at one end, as illustrated at 11, and having its opposite end suitably secured, as shown at 12, so that it cannot be tampered with, and yet can be raised to permit inspection of the mechanism therein. Housed by this casing, is a motor 13, which may be of any desired character, and either of the direct or A. C. type. This motor, as shown, is carried by a bracket 14 secured to the end of a suitable frame 15 in which is mounted a transverse crank shaft 16, the same being provided with ball bearings 17. The crank shaft 16 extends across a chamber 18, and a worm gear 19 is mounted on said shaft within the chamber. The lower portion of this chamber constitutes an oil well, it being understood that the worm wheel thus passes through a body of lubricant. Connected to the motor 13, is a shaft 20 that is located in the upper portion of the chamber 18 transversely to the shaft 16. This shaft 20 carries a worm 21 that meshes with the worm wheel 19, so that rotary motion is thus imparted to the shaft 16.

On one of the projecting ends of the shaft 16 is mounted a crank 22 having a wrist pin 23, which is journaled on one end of a pitman 24. The other end of this pitman has a pivotal connection 25 with an arm 26 carried by a rock shaft 27 journaled on the base 9 and projecting through the opposite sides of the boxing 10. The crank 22 and arm 26 are of such proportion that as the crank 22 rotates, the arm 26 is given a back and forth or swinging motion.

Suspended from the projecting ends of the rock shaft 27 are tubular arms 28 supporting at their lower ends an open-ended tubular hood 29 that constitutes a connection between the arms. In this hood is located a suitable electric lamp 30, the leads 31 for which pass through the tubular arms 28. The hood 29 is provided on opposite sides of the lamp 30 with suitable signal lenses 32 which may be of any desired construction. Said hood is furthermore surrounded by a signal disk or plate 33 attached thereto by brackets 34 and preferably braced by a cross bolt 35 that connects the arms 28 above the hood.

Located on the base 9 are insulation blocks 36, two being shown. Each of these blocks

is provided with binding posts designated respectively 37 and 38. From the binding posts 37 electrical conductors 39 lead to the motor 13. A suitable source of electricity is shown diagrammatically at 40 in Figure 6 has an electrical connection 41 with one of the binding posts 37, and also an electrical connection 42 with the other binding post. Suitable controlling means for this circuit 10 is employed, and is shown diagrammatically and designated 43. This controlling mechanism as is well known to those skilled in the art is actuated by the passage of a train, and may be of any well known or desired 15 character. To avoid unnecessary intricacy, it is only indicated in a generic character by a circuit closer. Connected to the binding posts 37 or the leads 41 and 42 is the lamp 30 as shown at 44, and if desired, a 20 signal bell 45 may also have similar connections, as shown at 46.

A brake for the motor is also provided. This brake is shown in detail in Figure 8. A brake wheel 47 is mounted on the motor 25 shaft, and cooperating with this wheel is a spring band 48 having a friction element 49. The band has one end offset as shown at 50, said end being secured to a post 51, while the other end has secured to it a 30 plunger armature 52 that operates in a solenoid 53. The solenoid is connected with the binding post 37 or the leads 41—42 by wires 54. Under ordinary conditions, or when the 35 solenoid 53 is deenergized, the brake band will by its own resiliency, be held against the brake wheel 47, but when the solenoid is energized, the plunger 52 will be drawn thereinto, thus carrying the brake band out of engagement with the wheel, so that the 40 motor may operate without resistance therefrom.

Mounted on the rock shaft 27 and insulated therefrom is a cam 55 constituting one element of a circuit controller, the other 45 element comprising a spring contact element 56 that is engaged and disengaged by the cam 55 upon the oscillation of the rock shaft 27. The cam element 55 is electrically connected to one of the binding posts 37 as shown at 57 in Figure 6, and is thus connected through the motor 13 with one side of the source of electrical energy 40. The contact element 56 is electrically connected through the binding post 38, wire 58, and a 50 portion of the wire 42 with the opposite side of the source of electrical energy, so that a circuit is established through the circuit closer 55—56 when the contact elements thereof are in engagement, said circuit including the source of electrical energy 40 and the motor 13.

As is well known in railroad circles, the "safety" position of a signal is at the left, or as shown in Figure 1, and assuming that 60 the parts are in this position with the cir-

cuit controller 43 open, and the circuit controller 55—56 open, all the electrical devices will be inactive. As a consequence the brake band will be engaged with the brake wheel 47. If now, the circuit controller 43 is 70 closed by an approaching train, the circuit will be established as follows. Beginning at the source of electrical energy 40, through the wire 42 and circuit closer 43, to one of the binding posts 37, thence through the 75 motor 13 by one of the wires 39, back through the other wire 39 to the other binding post 37 and wire 41 to the source of electrical energy 40. The motor 13 is thus thrown into operation, and simultaneously 80 the bell 45 and lamp 30 will be operated. The closing of this circuit will simultaneously cause energization of the solenoid 53 so that the brake band will be withdrawn from the brake wheel 47. The motor will thus be thrown into operation, causing the swinging 85 of the signal back and forth, while the lamp 30 within the housing is illuminated. As the train passes the crossing through 90 suitable mechanism well understood, the circuit controller 43 will be opened and the above described circuit will be broken. This would of itself cut off the motor 13, the solenoid 53, the bell 45 and the lamp 30 95 from the source of electrical energy, and the signal would immediately be stopped. It will be clear, however, that this breakage of the circuit may happen at any time, irrespective of the position of the signal, but if said signal is in any other position than the predetermined "safety" position, shown 100 in Figure 1, it will be noted that the cam 55 will be in contact with the element 56, and as long as this contact takes place, the circuit will be established and maintained 105 from the source of electrical energy 40 through the wire 58, binding post 38, contact element 56, contact element 55, the wire 57, one of the wires 39, the motor 13, the other wire 39, and the wire 41 to said source 110 of electrical energy. The motor therefore will continue to operate until the cam 55 disengages the contact element 56, and this disengagement will take place only when the signal is at said "safety" or "clear" position, whereupon all the parts will be de- 115 energized, the brake will be applied, the motor will stop, while the light will be extinguished, and the bell will cease its operation. 120

From the foregoing, it is thought that the construction, operation and many advantages of the herein described invention will be apparent to those skilled in the art, without further description, and it will be understood that various changes in the size, shape, proportion and minor details of construction, may be resorted to without departing from the spirit or sacrificing any of the advantages of the invention. 130

Having thus fully described my invention, what I claim as new, and desire to secure by Letters Patent, is:—

1. In signal apparatus of the character set forth, the combination with a movable signal member, of an operating motor therefore, connections between the motor and signal member for continuously driving the latter by the former, means independent of the operating motor for controlling the operation of said motor, means controlled by the operating motor for also controlling said operating motor and continuing the movement of the signal by said operating motor when the first controlling means is inactive until said signal reaches a predetermined safety position, said second controlling means then becoming inactive, and means for stopping the operating motor and signal in said predetermined safety position when the second controlling means is inactive. 70
2. In signal apparatus of the character set forth, the combination with a swinging signal member, of a motor, means for effecting a continuous operation of the motor in one direction, operating means for repeatedly and automatically swinging said signal member in both directions by said motor when so operated, means independent of the operating means for controlling the operation thereof, means controlled by the operating means for also controlling said operating means and effecting a continuing movement of the signal by said operating means when the first controlling means is inactive until said signal reaches a predetermined position, said second controlling means then becoming inactive when the operating means and signal are in a predetermined position, and means controlled by the second controlling means for automatically locking said signal when said predetermined position is reached. 80
3. In signal apparatus of the character set forth, the combination with a movable signal member, of a motor, means for continuously operating the motor in one direction, connections for effecting both a back and forth movement of the signal member by the motor when so operated, mechanism for controlling the actuation of the operating motor, and means for continuing the operation of the motor to move the signal member to and secure its stoppage at a predetermined position after the controlling mechanism is operated to stop the actuation of the operating motor. 90
4. In signal apparatus of the character set forth, the combination with a movable signal member, of a motor having connections with the signal for positively operating it at all times when the motor is in operation, and mechanism for controlling the movement of the signal member, includ- 100
- ing means for throwing the operating motor into and out of action, and means for continuing the action of the operating motor when the first means is inactive to continue the movement of the signal by the motor to a predetermined position. 105
5. In signal apparatus of the character set forth, the combination with a movable signal member, of means constantly movable in one direction for operating it, permanent connections between the operating means and signal member for causing a back and forth movement of the latter by the former, and mechanism for controlling the movement of the signal member by said means, including means for throwing the operating means into and out of action, and means controlled by the signal operating means for continuing the action of the operating means when the first controlling means is inactive to continue the movement of the signal to a predetermined position and stopping the action of the operating means as soon as said position is reached. 115
6. In signal apparatus of the character set forth, the combination with a swinging signal member, of an electric motor, driving means between the motor and signal member for effecting an automatic continuous movement of the signal member in both directions by the motor, electrical means for continuously driving the motor in one direction, comprising two circuits that include said motor, means independent of the motor for controlling one of the circuits without affecting the other, and means operated by the motor for controlling the other circuit. 120
7. In signal apparatus of the character set forth, the combination with a movable signal member, of an electric motor for actuating the same, and electrical means for effecting a continuous operation of the motor in one direction when energized and for controlling such operation, including separate circuits including the motor and controlling devices in the respective circuits, one of which is actuated by the motor and the other being capable of actuation independently of said motor. 125
8. In signal apparatus of the character set forth, the combination with a movable signal member, of an electric motor for actuating the same, driving connections between the motor and signal member for constantly driving the latter by the former whenever the motor is in operation, and means for controlling the actuation of the motor, including automatic mechanism for throwing the motor into action, a controlling device actuated by the motor for continuing the operation of said motor when the automatic mechanism becomes inactive, and stopping the motor when the signal is in a predetermined position, and means for 130

locking the signal upon the operation of the second controlling device.

9. In signal apparatus of the character set forth, the combination with a signal member movable to and from a predetermined inactive position, of an electric motor, driving connections between the motor and signal member that causes the positive movement of the latter by the former both to and from such inactive position, a circuit including the electric motor, a controller for said circuit independent of the motor, another circuit including the motor, a controller for the second circuit, and means actuated by said motor to operate the controller of the second circuit when the signal member approaches its said predetermined inactive position.

10. In signal apparatus of the character set forth, the combination with a swinging signal, of a rock shaft supporting the same, an electric motor, gearing connecting the electric motor and rock shaft, a circuit controller comprising a cam element on the rock shaft, and a spring contact element cooperating with the cam element, a circuit including the circuit controller and the motor, another circuit controller operable independently of the motor, and a circuit including the last mentioned controller and the motor.

11. In signal apparatus of the character set forth, the combination with a signal, of an electric motor for automatically effecting a prolonged continuous operation thereof, two actuating electrical circuits including the said motor, a controlling device for one circuit operable independently of the motor, a controlling device for the other circuit operated by the motor and effecting the operation of said motor after the first circuit is inactive to cause the signal to assume a predetermined position, and an electrically operated holding device for the signal controlled by both circuits and immediately operating to secure the signal in said predetermined position when the second circuit becomes inactive.

12. In signal apparatus of the character set forth, the combination with a signal, of an electrical motor for automatically effecting a prolonged continuous operation there-

of, two actuating electrical circuits including the said motor, a controlling device for one circuit operable independently of the motor, a controlling device for the other circuit operated by the motor and effecting the operation of said motor after the first circuit is inactive to cause the signal to assume a predetermined position, and an electrically operated holding device included in both circuits and held inactive by either, said holding device immediately operating to secure the signal in said predetermined position after the first circuit becomes inactive and immediately upon the second circuit becoming inactive.

13. In signal apparatus of the character set forth, the combination with a casing, of a rock shaft mounted therein, spaced arms carried by the rock shaft, an open ended tubular hood connecting and carried by the free ends of the arms, a signal plate surrounding and secured to the hood, a lamp located within the hood, an electric motor in the casing, gearing between the motor and rock shaft for swinging the latter, electric means including a circuit for operating the motor and illuminating the lamp, a controller for the circuit, and a second controller for the motor including coacting elements, one of which is mounted on and moves with the rock shaft.

14. A crossing signal comprising a pendulum semaphore, a motor, driving connections between said motor and semaphore that cause the positive movement of the latter in both directions by the former on its continuous movement in one direction for effecting the oscillation of said semaphore, a circuit for energizing said motor to effect its continuous movement in one direction, a contact for opening and closing said circuit, and means for continuing the energization of said motor to continue its movement in the same direction after said contact has been opened and until the semaphore reaches a predetermined inclined position.

In testimony whereof, I affix my signature in the presence of two witnesses.

WILL C. NEAHR.
